UNITED STATES PATENT OFFICE.

GEORGE W. PARRY, OF INDIANAPOLIS, INDIANA.

BREECH-LOADING GUN.

No. 893,866.

Specification of Letters Patent.

Patented July 21, 1908.

Application filed October 26, 1907. Serial No. 399,258.

To all whom it may concern:

Be it known that I, GEORGE W. PARRY, a citizen of the United States, residing at Indianapolis, in the county of Marion and State of Indiana, have invented certain new and useful Improvements in Breech-Loading Guns; and I do declare the following to be a full, clear, and exact description of the invention, reference being had to the accompanying drawings, and the letters and figures of reference marked thereon, which form a part of this specification.

This invention relates to the double barrel type of guns that are fired by means of a single trigger, the invention having reference particularly to improvements in the trigger and the safety lock therefor, and a device for releasing the barrel locking apparatus, so that the top lever may return to its normal position in order that the stock when separated from the barrels may be packed conveniently in a carrying case.

Objects of the invention are to improve various features of breech-loading guns to enable them to be handled safely and operated conveniently and expeditiously, and to provide an improved single trigger for double barrel guns that will permit either barrel to be fired in succession without firing the remaining barrel, and also to permit of firing either barrel first and the remaining barrel immediately afterward, a further object being to provide means for releasing the barrel-lock when latched in open position so as to permit return of the top lever to normal position.

The invention consists in an improved double barrel gun trigger provided with a reversing trip-block for operating either hammer sear at will, the trigger being provided also with an alternate trip block for operating the other sear automatically if desired after one sear has been operated, the trigger being provided also with a trip-block detent for holding the alternate trip-block away from the sears when not required for use.

The invention further comprises a recoil safety lock to prevent accidental discharge of the remaining barrel after firing one barrel, the detent holding the alternate trip-block away from the sears so as to prevent simultaneous discharge of both barrels.

The invention consists further in providing a push bar for releasing the lock mechanism operated by the top lever, so that the top lever may return to its normal position after

having unlocked the gun barrels from the frame; and the invention consists further in certain novel parts and in the combinations and arrangements of parts as hereinafter particularly described and defined in the appended claims.

Referring to the drawings Figure 1 is a side elevation of a double barrel breech loading shot gun having a single trigger, all constructed substantially in accordance with the invention; Fig. 2, a top plan of the frame and stock of the gun in which a portion of the stock is broken away; Fig. 3, an inverted view of the parts shown in the preceding figure; Fig. 4, a transverse sectional view approximately on the line A in Fig. 2; Fig. 5, a fragmentary plan view of the barrels inverted; Fig. 6, a transverse sectional view approximately on the line B B in Fig. 2; Fig. 7, a top plan of the fore-end complete separate from the remaining parts of the gun; Fig. 8, a longitudinal sectional view approximately on the line C in Fig. 2 with the stock omitted; Fig. 9, a fragmentary longitudinal sectional view approximately on the line D in Fig. 2 with the stock omitted and a portion of the fore-end iron joining the frame; Fig. 10, a fragmentary longitudinal sectional view on the line E in Fig. 2; Fig. 11, a fragmentary transverse sectional view approximately on the line F F in Fig. 9; Figs. 12, 13 and 14, fragmentary elevations showing the trigger mechanism in different positions; Fig. 15, a fragmentary horizontal sectional view on the line G in Fig. 9; Fig. 16, a fragmentary vertical longitudinal central sectional view of the trigger as on the line E in Fig. 2; Fig. 17, a fragmentary perspective view of the improved trigger; Fig. 18, a fragmentary longitudinal sectional elevation showing the arrangement of a cartridge ejector with the frame as on the line D in Fig. 2 or H in Fig. 7; Fig. 19, a fragmentary top plan of the trigger plate with portions in horizontal section; Fig. 20, a fragmentary vertical central sectional view of the recoil safety lock as on the line E in Fig. 2; Fig. 21, a perspective view of a trip-block detent inverted which comprises a part of the improved trigger; Fig. 22, a fragmentary detail view of the safety slide; Fig. 23, a fragmentary longitudinal sectional view as on the line C in Fig. 2, showing the lock mechanism in different positions from those appearing in preceding figures; Fig. 24, a side elevation of the ejector mechanism separate from

the other parts of the gun; Fig. 25, a longitudinal sectional view on the line I in Fig. 7, but partly broken away; Fig. 26, a fragmentary longitudinal sectional view of the ejector 5 associated with the frame as on the line E in Fig. 2 or J in Fig. 7; Fig. 27, a transverse sectional view on the line K-K in Fig. 24; Figs. 28 and 29 perspective views of the right and left-hand ejector sears; Fig. 30, a rear end 10 elevation of the fore-end and ejectors; Fig. 31, a perspective view of one of the ejector hammers; Fig. 32, a perspective view of the reversing trip-block comprising a part of the improved trigger; Fig. 33, a perspective view 15 of one of the sears for the firing hammers; Fig. 34, a top plan of the main parts of the trigger; Fig. 35, a perspective view of the barrel lock; Fig. 36, a perspective view of the top lever, having improvements connected therewith; and, Fig. 37, a front elevation of 20 the alternate trip-block.

Similar reference characters in the various figures of the drawings designate corresponding elements or features of construction.

25 In the drawings the numeral 1 designates the gun stock; 2, the frame having the usual hinge end 2'; 3, the top tang of the frame; 4, the trigger plate; 5, the fore-end wood; 6, the fore-end iron having the usual hinging 30 end 6'; 7 and 8, the gun barrels provided with the usual hinging hook 9 for connection with the pivot 10 in the hinging end 2' of the frame, the upper portion of the frame having a recess 11 therein to receive the lug 12 that 35 is attached to the rear ends of the barrels. The upper portion of the frame is provided with a hollow cylindrical lock 13 shown in Fig. 35 having a longitudinal slot 14 in its wall to receive the lug, the lock being 40 mounted rotatively and having a transverse slot 15 extending from the slot 14 so as to form a curved bolt 16 adapted to be projected through a suitable opening in the lug 12 for locking the barrels to the frame. The 45 forward end of the lock 13 has a recess 17, at one end of which is a notch 18 in the exterior of the wall of the lock, the opposite end of the lock having an aperture 19 in its end adjacent to the wall thereof.

50 The interior of the frame 2 is provided with a journal bearing 20 arranged a short distance above the trigger plate, and a shaft 21 is journaled in the bearing and also in the tang 3, and has the top lever 22 suitably 55 mounted on the top thereof so as to operate in the usual manner upon the tang for unlocking the barrels, the shaft being turned by the lever, the lever having a jaw 23 pivotally connected thereto the jaw having a 60 finger 24 extending into the aperture 19 for rotatively operating the lock 13. Arms 25 and 26 are attached to the shaft 21 near the lower end thereof, and the arm 25 is engaged by a plunger 27 that is forced against the 65 arm by a spring 28 seated in the frame which

constitutes the top lever spring for normally holding the bolt 16 in its locking position, the bolt 16 being held in unlocking position by a latch bolt 29 that is mounted in the frame and movable vertically by a spring 30 70 and having a rear guide face 31 in engagement with the lock 13 in the recess 17, the latch bolt having a shoulder 32 adapted to enter the notch 18 whereby the lock 13 is held against rotative movement with the top lever 22 projecting over one side of the stock as indicated by dotted lines in Fig. 2, so as to be obstructive when placing the gun stock in a traveling case. Ordinarily the lever may be permitted to move to its normal 75 position only by swinging the gun barrels so that the lug 12 engages and pushes down the latch bolt 29 out of the notch 18, or by inserting some instrument into the recess 11 and forcing the latch bolt 29 downward by 80 hand, the latter operation being usually inconvenient, the latch bolt 29 being normally forced upward by the spring 30. The latch bolt 29 has an inclined face 33 opposite which a guide bore 34 is formed in the frame 85 and supports a push bar 35 having a V-shaped notch 36 in its side in which is seated a V-shaped catch 37 guided in a recess 38 and normally held yieldingly in the notch by a spring 39, the inner end of the push bar 90 having an inclined face 40 to engage the shoulder 33, so that if the push bar 35 be forced inward, the latch bolt 29 will be forced downward out of the notch 18, the catch 37 causing retraction of the push bar 95 and holding it in its normal position, and also the inclined shoulder 33 may assist in retracting the push bar when the latter is released by the operator.

100 The hammers 41 and 42 are mounted in the frame in the usual manner on a pivot pin 43, the pivoted portions of the hammers being provided with wrist pins 41' and 42' respectively, and arranged above and forward of the pivot pin 43, the pivoted portions of 105 the hammers having curved forward faces 43', at the lower parts of which are projections 44 to be engaged by the sears 45 and 46 when the hammers are cocked, the sears being mounted as usual on a pivot pin 47 behind the hammers and extending rearward 110 above the trigger plate, the sears being normally forced into engagement with the hammers by suitable sear springs 48. The frame has suitable chambers 49 and 49' extending 115 in inclined directions from the chambers in which the hammers are mounted downward through the pivoting end 2' of the frame, and cocking rods 50 and 50' are mounted in the chambers and guided therein and have 120 hooks 51 and 51' engaging the wrist pins 41' and 42' respectively, so that the rods may push the hammers back to cocked positions 125 or draw them forward for firing, the latter operations being accomplished partly by 130

means of collars 52 and 52' which are secured to the rods, collars 53 and 53' that are loose on the rods and engage the curved faces 43' of the hammers, and springs 54 and 54', either spring seated between a pair of collars as 52 and 53, the springs being compressed and forcing the collars 53 and 53' against the bearing faces 43', so as to draw the pins 41' and 42' forward. A pair of push levers 55 and 55' are mounted in suitable recesses in the hinging end 2' and have each a projection 55" on the outer side thereof, the push levers being normally pressed against the cocking rods 50 and 50' by suitable springs 56 and 56', the push levers being preferably supported by a pivot pin 57. The hinging end 2' has a projection 58 on the top of the pivoting pin 10 for engagement with shoulders 59 on the under sides of the extractors 60 and 60' for operating the extractors a short distance in the usual manner in order to slightly withdraw the cartridge shells from the barrels when the latter are released by the top lever 22 and swung away from the frame. The push levers are employed as an intermediate means for cocking the hammers and for operating the ejectors, as will further appear, the projections of the push levers extending into openings 61 and 61' that are formed in the pivoting ends 6' of the fore-end iron, the pivoting end 6' having also an opening 62 between the other two openings and opposite a central recess that is formed in the companion pivoting end 2' to provide a shoulder 63 for actuating portions of the ejectors.

An ejector box 64 is suitably secured upon the top of the fore-end iron 6 and has a pair of ears 65 and 65' extending through a slot 6" in the fore-end iron, the ears supporting a pivot 66 below the fore-end iron. A pair of ejector hammers 67 and 67' are mounted in the ejector box and provided each with an arm 68 having projections 69 and 69' on the lower end thereof, preferably formed as ratchet teeth, the hammers being normally forced rearward, each by a spring 70 and held in retracted positions by ejector sears 71 and 71' having each a lateral arm 71", the sears being pivoted on the pin 66 between the ears 65 and 65', and the arms thereof extending opposite the openings 61 and 61', the sears normally engaging the projections 69 of the arms 68 and pressed by springs 72, the projections 69' of both arms 68 being engaged by an ejector detent 73 which is mounted also on the pivot 66 between the ejector sears and engaged by a spring 74. When "breaking" the gun, the shoulder 63 engages the detent 73 and releases both ejector hammers, and also if both barrels have been fired the projections 55" will engage the ejector sears and release them from the projections 69 so that both ejector hammers will strike the inner ends of the extractors 60 and 60' and throw the loosened shells out of the barrels. Also during the "breaking" movements the push levers 55 and 55' will be engaged by a bearing pin 57' that extends through the tops of the openings 61 and 61' to cock the hammers.

The top of the trigger plate 4 is provided with a post 75, in the under side of which is a recess 4' extending through the trigger plate and in which the trigger main part 76 is mounted on a pivot 4" and normally held and pushed outward by a spring 77. In the upper portion of the main part of the trigger a reversing trip-block 78 is mounted rotatively and projecting through the sides of said main part, and provided with an operating lever 79 which extends through a suitable opening 79' in the trigger plate adjacent to which are designations 80 and 80' as "R" and "L" (shown in Fig. 3) indicating the right barrel and the left barrel respectively. The trip-block is held in either one of two positions by means of a spring 81 forcing a plunger 82 into depressions 82' in the trip-block, the end portions of the trip-block having flat sides 83 and 83' whose faces are in different planes. The trip-block extends under the rear ends of the sears 45 and 46 and may trip either one of the sears only without being manually readjusted, it being designed that the trip-block may be adjusted rotatively by means of the lever 79 so that the flat side 83 may be turned towards the right-hand sear when it is not desired to fire the right-hand barrel, the block being adapted to fire the left-hand barrel in this position, or when desired to fire the right-hand barrel and not the left-hand barrel the flat side 83 will be brought around opposite to the left-hand sear. The main trigger part has a recess 76' in the top thereof rearward of the trip block 78 and an alternate trip block 84 is mounted in the recess on a pivot 84' and extends upwardly past the rear ends of the sears 45 and 46, but lateral arms on the trip block may be moved under the ends of the sears under certain conditions, so that after one sear has been tripped by the trip block 78, then on pulling the trigger a second time the remaining sear may be tripped by the trip block 84, the latter having two laterally extending arms 85 and 85' for engaging the under sides of the sears. The trip block 84 is normally pressed forward or towards the sears by a spring 86 mounted in a chamber 76" of the trigger main part and supported by a plug 86' inserted in the chamber.

A housing 87 is mounted on the post 75 or may be otherwise supported and has a push bar 88 mounted slidably therein and normally pressed against the arm 26 by a spring 89 mounted in the housing, the push bar being employed for pushing the alternate trip block 84 away from the sears to its inoperative position when the top lever 22 is oper-

ated to unlock the gun barrels from the frame, and the trip block 84 is normally held in such inoperative position by means of a trip block detent 90 which is supported on the trigger main part 76 by a pivot 90' rearward of the trip block 84. The detent has a pair of hooks 91 and 91' on the forward end thereof adapted to engage the arms 85 and 85' for holding the trip block 84 in its inoperative position and having also a hook 92 on its opposite end, the two hooks being automatically held in engagement by a spring 93. A standard 94 is mounted fixedly on the top of the trigger plate 4 rearward of the trigger and supports a recoil safety lock 95 which is suitably weighted and swings on a pivot 95' that is connected to the standard, the lock having a hook 96 adapted to automatically engage the hook 92 when the gun is fired to prevent the outward or downward movement of the trigger to its full extent, and therefore prevent the movement of the arms 85 and 85' downward sufficiently to pass under the sears. The standard is provided with a stop shoulder 94' adapted to be engaged by the rearward end of the detent 90 when the trigger is operated for disconnecting the hooks 91 and 91' from the arms 85 and 85', so that the trip block 84 may be moved forward against the rear ends of the sears. The safety lock 95 is normally forced rearwardly and away from the detent 90 by a spring 97 seated therein and engaging the standard 94. The standard supports a safety bar 98 which is mounted pivotally on a pin 98' on the top of the standard, the bar being controlled by a slide 99 that is mounted in a slot 3' of the tang 3, and has a projection 100 provided with a pin 101 connecting a reach rod 102 therewith that is connected to the upper end of the safety bar 98, so that the lower end of the safety bar may be moved onto the top of the alternate trip block 84 to positively prevent operation of the trigger. The slide 99 is prevented from being moved accidentally by means of depressions 103 that are formed in the reach rod, and a plunger 104 mounted in a suitable recess in the tang 3 and forced by a spring 105 against the reach rod, so that the latter becomes latched when the plunger enters either one of the recesses.

In practical use the gun may be operated and fired in substantially the same manner as similar guns have heretofore been used. If it is preferred to fire both barrels, first the right-hand and then the left-hand barrel, the lever 79 should be moved forward toward the letter "R" and no further manual adjustment will be required for firing the barrels in succession alternately. If the trigger be pulled the trip-block 78 will engage and trip the right-hand sear 45 which will cause the right-hand barrel to be fired, and the rebound will cause the safety lock 95 to engage

the detent 90 and hold back the alternate firing block 84 which as will be understood had been pushed back during the loading operations and caught by the detent. During the rebound if the trigger has been involuntarily pulled, the other barrel will not be fired, but the detent 90 would engage the shoulder or projection 94' and cause the detent to release the trip block 84, so that when the trigger descends the mechanism will be ready to fire the remaining barrel, since the arm 85' will pass under the sear 46 which may be tripped thereby when the trigger is again pulled. If the detent 90 is not released involuntarily from the trip block 84 and the safety lock 95, as above-mentioned, this should be accomplished by pulling the trigger purposely, after which the trigger may be pulled to fire the gun. If it is desired to fire the left-hand barrel first and then the other one repeatedly, the lever 79 should be moved to its opposite position. In case that it be desired to keep a loaded cartridge in one barrel and fire the other barrel repeatedly, this may be done by simply pulling the trigger once after reloading the barrel each time that it may have been fired, since either sear may be operated by the trip block 78 without disturbing the other sear which cannot be operated by the alternate trip-block 84 if the trigger is permitted to remain at rest after firing the barrel which it may have been predetermined to fire alone. After operating one hammer the cocking rod of that hammer will be in its forward position as in Figs. 8 and 18, while the other rod will remain as in Fig. 9. If then the barrels be unlocked and swung on their pivot, the push lever 55 would be projected against the pin 57', and the projection 55" would engage the sear 71 so as to release it from the projection 69, and with a further movement of the barrels on their pivot the shoulder 63 will engage the detent 73 and disconnect it from both of the projections 69', thus releasing the ejector hammer 67 for throwing out the empty shell, while the other ejector sear will restrain the other ejector hammer. Other results of the operations of the gun will be readily understood from the foregoing descriptions in detail.

Having thus described the invention, what is claimed as new is—

1. A gun-trigger including a main part with a pivotal axis, an alternate trip-block mounted movably on the main part and spring-pressed towards the pivotal axis thereof, a detent pivoted to the main part and spring-pressed to hold the trip block when the latter is moved reversely away from the pivotal axis.

2. A gun-trigger including a main part with a pivotal axis, and a reversing trip block mounted rotatively in the main part with its axis parallel to the pivotal axis of the main part, the trip block being cylindrical and

having two recessed side portions whose faces are in different planes and at opposite side of the main part.

3. A gun-trigger including a recessed main part with a pivotal axis, an alternate trip-block having a lateral arm thereon and pivoted in the recess of the main part, a spring mounted in the main part and normally pressing the trip-block towards the pivotal axis, a detent pivoted to the main part and spring-pressed to hold the trip-block when the latter is moved reversely away from the pivotal axis.

4. A gun-trigger including a main part
15 with a pivotal axis, a reversing trip-block
mounted rotatively in the main part with its
axis parallel to the pivotal axis of the main
part, the trip-block having two recessed side
portions whose faces are in different planes
20 and at opposite sides of the main part, one
end of the trip-block having an operating de-
vice thereon, the middle portion of the trip-
block having depressions in the side thereof,
and a latch device mounted in the main part
25 and spring-pressed against the trip-block to
enter either one of the depressions.

enter either one of the depressions.

5. A gun including a trigger comprising a main part, a cylindrical reversing trip block mounted rotatively on the main part and having an operating lever and also two flat side portions whose faces are in different planes, means for latching the block against rotative movements, an alternate trip block pivoted to the main part and spring-pressed towards the reversing trip block, and a detent pivoted to the main part and spring-pressed to hold the alternate trip block when the latter is moved reversely away from the reversing trip block.

40 6. A gun including two sears, a trigger plate, a trigger main part pivoted to the trigger plate and having a reversing trip block mounted thereon adjustably under the two sears to engage either one only of the sears
45 when the main part is moved, an alternate trip block pivoted to the main part and having two arms movable to or under the ends of the sears, a spring normally pressing the alternate trip block towards the sears, a detent pivoted to the trigger main part and spring pressed into engagement with the retracted alternate trip block, a standard supported fixedly on the trigger plate and having a projection to be engaged by the detent to release
50 the alternate trip block, a recoil safety lock pivoted to the standard and movable into locking engagement with the detent to temporarily limit the downward movement of the trigger and prevent premature movements of the arms of the trip block beneath the sears, and a spring pressing the safety lock away from the detent when released therefrom.

7. A gun including a frame with a top
55 tang, a trigger plate, two sears, a trigger

main part pivoted to the trigger plate and having a reversing trip block and also an alternate trip block mounted thereon to trip the sears separately, the alternate trip block being movable to the sears and also movable by the main part towards the tang, a spring normally pressing the alternate trip block to the sears, a detent mounted on the main part for temporarily holding the alternate trip block away from the sears, means for automatically disengaging the detent from the alternate trip block, a safety bar controlled and movable manually against a part of the trigger to lock the trigger against operative movements towards the tang, and a recoil safety lock movable automatically into locking engagement with the detent to temporarily limit the downward movement of the trigger and prevent engagement of the safety bar with the trigger part.

8. A gun including a frame with a top tang, a trigger plate, two sears, a trigger main part pivoted to the trigger plate and having a reversing trip block and also an alternate trip block mounted thereon to trip the sears separately, the alternate trip block being pivoted and movable to the sears and also movable by the main part towards the tang, a detent mounted on the main part for temporarily holding the alternate trip block away from the sears, a standard mounted fixedly on the trigger plate and having a safety bar mounted thereon that is movable against the alternate trip block when the same is held by the detent, and means for disengaging the detent from the alternate trip block when said block is not engaged by the safety bar.

9. A gun including a frame, a trigger plate, two sears, a trigger main part pivoted to the 105 trigger plate and having a reversing trip block and also an alternate trip block mounted thereon to trip the sears separately, the alternate trip block being pivoted and movable to or from the sears, a spring normally 110 pressing the alternate trip block to the sears, a push-bar for moving the alternate trip block away from the sears, a detent for holding the alternate trip block away from the sears, means for releasing the alternate trip 115 block from the detent, a top lever, a shaft connected to the top lever and mounted in the frame, an arm on the shaft for operating the push-bar, gun barrels pivoted to the frame, and a lock for the barrels connected 120 with the shaft.

10. A gun including a trigger plate, two sears extending opposite to the plate, a trigger main part pivoted to the plate to trip either one of the sears and having an alternate trip block mounted pivotally thereon to trip the other one of the sears, a standard mounted fixedly on the trigger plate, and having a stop shoulder, a recoil safety lock pivoted to the standard and having a nose 125 130

thereon, a detent pivoted between its ends to the trigger main part and having hooks on its ends, the hook on one end of the detent being engageable with the alternate trip block to hold the same away from the sear and the other hook being engaged by the hook of the safety lock during recoil to prevent the alternate trip block being carried under said sear, said detent being moved into contact with said stop shoulder to release said block when the trigger is pulled to trip one sear, and a spring to draw the hook of the safety lock away from the hook of the detent when the trigger is pulled a second time to permit the alternate trip block to drop into engagement with the other sear for tripping the same.

11. A gun including a frame, a trigger plate, two sears extending opposite to the plate, a trigger main part pivoted to the plate to trip one of the sears and having an alternate trip block mounted thereon for tripping the other sear, a spring normally pressing the alternate trip block to the sears, a housing supported opposite to the trigger plate, a push-bar guided in the housing and movable against the alternate trip block to move the same away from the sears, a spring engaging the housing and the push-bar to retract the latter, a detent to engage the alternate trip block and hold the same when moved away from the sears, means for automatically operating the push-bar, and means acting to disengage the alternate trip block from the detent when the trigger main part is pulled to trip one sear, safety locking means acting to prevent engagement of the block with either sear during and after said pulling of said main part, and means acting to move said locking means to permit the block to move into engagement with the other sear when said main part is pulled a second time.

12. In a gun, the combination of a frame having a guide-bore in a side thereof, a push-bar mounted slidably in the guide-bore, and a spring-pressed latch-bolt in the frame having an inclined shoulder adjacent to the inner end of the push-bar to be engaged thereby for retracting the latch-bolt, with a gun-barrel hinged to the frame, a barrel-lock in the frame to be held in unlocked position by said latch-bolt, and a top-lever for operating the barrel-lock.

13. In a gun, the combination with a frame, a rock-shaft mounted in the frame with a top lever thereon, two pivoted sears, a trigger-plate, and a trigger main part pivoted to the trigger-plate, of a reversing trip-block mounted on the main part, an alternate trip-block mounted on the main part to actuate the sears, a spring mounted on the main part and normally holding the alternate trip-block to the sears, a detent for holding the alternate trip-block away from the sears, a push-bar mounted slidably for pushing the

alternate trip-block into engagement with the detent, and an arm on the rock-shaft to engage and operate the push-bar when the top lever is moved.

14. In a gun, the combination of a frame provided with a spring-pressed catch mounted therein and having a V-shaped end, a push-bar mounted slidably in the frame across the V-shaped end, and having a V-shaped notch therein normally receiving said end, and a spring-pressed latch-bolt having an inclined shoulder to be engaged by the push-bar for retracting the latch-bolt, with a gun-barrel hinged to the frame, a barrel lock in the frame to be held in unlocked position by said latch-bolt, and a top lever for operating the barrel lock.

15. In a gun, the combination with a trigger-plate, and two pivoted sears, of a trigger main part pivoted to the plate, a trip-block on the main part to actuate one of the sears and having an operating lever thereon that normally extends through the trigger plate, an alternate trip-block pivoted on the main part to engage and actuate the other one of the sears, a detent pivoted on the main part to engage and hold the alternate trip-block away from the sears and having a hook thereon, a pivoted safety lock having a hook to engage the hook of the detent, and a fixed stop device to be engaged by the detent for disengaging it from the alternate trip-block.

16. In a gun, the combination with a trigger-plate, a trigger main part pivoted to the trigger-plate, a slotted tang, and a sear, of a trip-block pivoted on the trigger main part and spring-pressed to operatively engage the sear, a detent pivoted on the main part to engage and hold the trip-block away from the sear, a safety-bar movable to a position opposite the trip-block to lock the main part, a slide on the tang having operative connection with the safety-bar, and a fixed stop device to be engaged by the detent for disengaging it from the trip-block.

17. In a gun, the combination with a trigger plate, and two sears, of a trigger part pivoted to the plate and having a member provided with a hook, a trip-block supported on the main trigger part to be moved into engagement with the sears when said trigger part is retracted, a standard secured on the trigger plate, a safety lock pivoted to the standard and having a hook to engage the hook of said member for preventing retraction of the main trigger part, and a spring acting to hold said lock hook away from the hook of said trigger member.

In testimony whereof, I affix my signature in presence of two witnesses.

GEORGE W. PARRY.
